UNITED STATES PATENT OFFICE.

CARL G. BUTTKEREIT, OF TOLEDO, IOWA.

IMPROVEMENT IN BELL-PIANOS.

Specification forming part of Letters Patent No. 142,768, dated September 16, 1873; application filed June 7, 1873.

To all whom it may concern:

Be it known that I, CARL GUSTAV BUTTKEREIT, of Toledo, in the county of Tama and State of Iowa, have invented a new and useful Improvement in Bell-Pianos, of which the following is a specification:

Figure 1 represents a sectional side view of my improved bell-piano action with parts broken off; Fig. 2, a front view of my improved bell-piano, showing arrangement of bells and key-board; and Fig. 3, a detail side view of the bell-hammer.

Similar letters of reference indicate corresponding parts.

The object of my invention is, mainly, to so arrange the different parts of bell-pianos that clear and pleasing effects may be obtained, and the working of the same be greatly perfected. My invention consists in actuating bell-hammers, dampers, pedals, and devices for modifying the tones of the bells, in connection with the method of suspending them, as is herein-after fully described, and subsequently pointed out in the claims.

A in the drawing represents one of the keys of the instrument, there being a row of keys arranged on a key-board similarly as on an ordinary piano-forte. Every key A is provided, on its rear part, with a short piece, a, to which is pivoted the upright piece b, which again connects, at its upper end, with a horizontal lever, d. Lever d is hinged, at its rear end, to a bar or piece, d', which is nearly parallel to d, and rigidly attached to a main support or standard, B, which is slightly inclined toward the vertical axis of the instrument, and supported, with the similarly-inclined support B', by the lateral top and bottom connecting-pieces C of the outer frame or case D of the bell-piano. The parts which form the bell-hammer action are applied to support B, while the parts, which produce the damper action are attached to support B'. To the upper side of lever d is connected, by suitable screws e, the intermediate lever f, to whose front end is pivoted the elbow or knee joint g. Its rear end carries the upright pillar h, which is provided, at its upper end, with a cushion, h', for the soundless arrest of the backward motion of the hammer. The elbow or knee joint g bears with its leg g'

against the lower side of the hammer-butt i, which is pivoted to a stationary arm, t', which is again supported, under a suitable angle, by the slotted arm l of support B. Leg g' passes through the slot of arm l. The rear leg g'' of elbow g passes below an adjustable pad, m, at the lower side of arm l, producing, by its gliding along pad m, the swinging motion of leg g', and its action on socket i. The stem i' is secured in socket i, and carries, at its upper end, the curved part of the hammer E, which is weighted, by suitable metal pieces p, at its front and rear end, to increase the momentum of its forward and backward stroke. The front end of hammer E is covered with cloth or leather binding; and the rear end provided with a downward-curved band-spring, n, which comes in contact with cushion h', arresting the backward motion of hammer E, as indicated in Figs. 1 and 3. On a pad at the rear end of key A rests the upright damper-rod o, which passes loosely through the pedal-bar F, and through a guide-lug, q, of damper-lever s, bearing, with a fixed pad, o', against lug q. A fixed pad, o'', of damper-rod o, supports the same on the lateral pedal-bar F, which slides in guides of frame D, being lifted, as desired, by means of pedal-rods r, pedal-levers r' and r'', which are pivoted to the bottom of frame D, and operated, by the pedal, in a similar manner as in pianos. The whole series of damper-rods o can, therefore, be lifted by the pedal-bar F, and the damper-action on the bells be discontinued at pleasure. The damper-lever s is pivoted between the upward-projecting lugs of damper-arm t, which is rigidly applied to support B'. Its front part is curved toward the lower edge of the bell, and has the cushioned damper G curved to suit the circumference of the bell. The rear end of lever s is weighted by metallic piece s', and connected, by lug q, with damper-rod o. Through the projecting rear end of arm t, which is covered with cloth or soft leather, passes the pin v of lever s, on which is placed, below arm t, the adjustable pad v', which defines the motion of the damper-lever s, and produces the noiseless working of the same.

When the key A is touched the damper G is withdrawn from the bell simultaneously

with the striking of the hammer E, being immediately drawn back again by its weighted end upon the bell, and arrests the vibrations of its component parts. When the pedal is used the damper-action is detached, and the sounds of the bell prolonged.

The bells H are placed on rods, with an inclination similar to that of the main supports B B'. The bell-rods I are hung to connecting-bars W of bell-frame L, which is preferably made of bronze or other suitable metal, and applied suitably to frame D of the instrument. The bell-frame L is placed above the sounding-board M, and in front of the hammer and damper actions, so that the bells are visible from the outside through glass doors of frame D. The bell-rod I is threaded along its full length, and hung, by a clamp, w', to the upper bar w; and, by its hook end, to the lower bar w. A curved rod, N, connects, by its eye y, the bell-rod I with the sounding-board M, being firmly held in place thereon by nuts z¹ and z². The bell H has, at its upper end, a tubular extension, a¹, which is lined, at its inside, with cloth or similar material. A rubber or leather cone and nut, a², secures the bell H to its proper plate on rod I from the outer, and a disk or cone and nut, a³, from the inner, side, so that the bell H is suspended in such a manner that a clear sound is produced without transmitting the vibrations to other parts. Bells of different sizes and pitch are strung upon rod I, and any series of them hung in bell-frame L, as desired. Their distance from each other corresponds somewhat to the distance of the keys on the key-board, the hammer and damper action of each bell being, by the inclination of the supporting-bars, arranged into a comparatively compact space. A second frame, P, is set in the rear part of bell-frame L, and may be lowered therein on the guide-ends p' of the pieces P', which are parallel to, and inclined in the same direction as, bell-rods I. A rod, b¹, connects the frame P to a lever, b², pivoted at the bottom of frame D, and connected thence to a second pedal in the same manner as the pedal-bar F. A lateral rod or piece, d², between pieces P', carries the leather apron e', which extends over the end of bell-hammer E, passing between the same and the bell-rod I when the frame P is lowered. The stroke of the hammer is thereby weakened, and a softer sound is produced. The effect of the bell-piano is thereby greatly varied, as not only clear musical sounds, with or without pedal action, but also stronger and weaker sounds may be produced.

Having thus described my invention, I claim as new and desire to secure by Letters Patent—

1. The combination of key A, pieces a b, arm d¹, levers d f, knee-joint g, arms l l', with adjustable pad m, hammer-butt i, and hammer E, forming the hammer-action, substantially as and for the purposes described.

2. The bell-hammer E, having weighted ends and curved band-spring n, for the purpose set forth.

3. The combination of the levers d and f, connected, by screws e, with pillar h and cushion h', for arresting back motion of hammer E, as described.

4. The combination of key A, damper-rod o, having pads or buttons o¹ o², damper-lever s, and arms t t', forming the damper-action, as described.

5. The damper-lever s, having curved and cushioned damper G, pin v, and pad v', weighted end s', and perforated lug q, for the purpose specified.

6. The inclined standards B and B', connected by pieces C, having stationary arms d¹ l l', and arms t t', respectively, to support hammer and damper action, substantially as set forth.

7. The arm l of standard B, having adjustable pad m, as set forth.

8. The sliding pedal-bar F, in combination with rods r, pivoted levers r¹ r², and pedal and pedal-rod, as specified.

9. The combination of pedal-bar E with damper-rods o and damper-levers s for disconnecting the damper action on the bells, substantially as described.

10. The bell-frame L, having lateral pieces W, in connection with bell-rod I, as specified.

11. The bell-rod I, in combination with sounding-board M, by supporting-rod N, having eye y and nuts z¹ and z², as set forth.

12. The combination of bell H with rod I by cones and nuts a² and a³, as described.

13. The frame P, having pieces P', guide-ends p', lateral pieces d², and aprons e, arranged and applied for the purpose set forth.

14. The combination of frame P with rod b¹, lever b², pedal-rod, and pedal, as and for the purpose described.

15. The combination of the subject-matter of the foregoing clauses, consisting of the hammer and damper action, damper-pedal, bell arrangement, tone-modifying frame, and pedal, with frame D, substantially as and for the purpose described.
